UNITED STATES PATENT OFFICE.

ALBERT G. BUZBY, OF PHILADELPHIA, PENNSYLVANIA.

IMPROVEMENT IN LAMPS.

Specification forming part of Letters Patent No. **150,824**, dated May 12, 1874; application filed December 10, 1873.

To all whom it may concern:

Be it known that I, ALBERT G. BUZBY, of the city and county of Philadelphia, State of Pennsylvania, have invented certain Improvements in Coal-Oil Lamps, of which the following is a specification:

My invention relates to improvements in coal-oil lamps having two wick-tubes; and the object of my invention is to increase the brilliancy of the flames in such lamps, by introducing to the same plentiful and separate supplies of air, in the manner fully explained hereafter.

In the vertical section, Figure 1 of the accompanying drawing, A represents the fountain or reservoir of the lamp; and consists, in the present instance, of a quadrangular casing, from which project the two flat tubes *a a* for receiving the usual flat wicks *b b*, the latter being controlled by the usual toothed wheels *d d* on spindles which project through the the casing. These wick-tubes are considerably wider than the wicks are thick, so that air admitted to the reservoir A, through elongated openings *x x*, can pass freely over the wicks through the said tubes. This is an important feature of my invention, for I have found after repeated tests that the air having free access to the reservoir, and having no other outlet therefrom than through the wick-tubes, enhances the brilliancy of the flame. A dome or hood, D, the character of which will be best understood by referring to the perspective view, Fig. 3, is placed over the wick-tubes, and rests with its lower edge on the top of the reservoir, this dome being closed at the top, with the exception of the elongated opening *e* for the flame, and having opposite perforated sides *f*, the latter forming, with the wick-tubes, two side air-chambers, *h h*, and two end air-chambers, *i i*, as best observed in the plan view, Fig. 4. These four air-chambers extend to the top of the wick-tubes, where all four communicate with the interior of the dome. The end chambers *i i* are separated from the side

chambers *h h* by partitions *m*, Fig. 4, air having access to the said end chambers through perforations *n* in the dome. In fact, all four chambers are separated from each other below the tops of the wick-tube, each chamber having a separate inlet for the admission of air—a feature which I have found to be of much importance, as it tends to produce a steady, uniform, and brilliant flame, free from smoke. Between the wick-tubes there is another air-chamber, having inlets *q* at opposite ends of the dome, (see Fig. 3), and across this air-chamber, at a short distance below the top of the wick-tube, extends a flat perforated plate.

It will thus be seen that air can gain access to the flame in seven directions, namely: through the two openings *x*, and through the reservoir and wick-tubes, through two side chambers, *h h*, through the two end chambers *i i*, and through the central air-chamber *p*, the result of this plentiful supply of air being a brilliant smokeless flame.

I claim as my invention—

1. A lamp provided with side openings *x* admitting air to the reservoir, and with a wick-tube having an internal channel, through which the combined air and vapor from the reservoir can pass over the wick to and out of the upper end of the wick-tube, as set forth.
2. The combination of the tubes *a a*, the dome D, and chambers *h h i i* having separate air-inlet passages, and all communicating within the dome above the wick-tubes, as set forth.
3. The combination of the tubes, dome, chambers *h h i i*, and central chamber *p*, all as described.

In testimony whereof I have signed my name to this specification in the presence of two subscribing witnesses.

ALBERT G. BUZBY.
